UNITED STATES PATENT OFFICE.

HENRY B. TILTON, OF PORTSMOUTH, NEW HAMPSHIRE, ASSIGNOR TO MORLEY BUTTON MANUFACTURING COMPANY, OF BOSTON, MASSACHUSETTS, A CORPORATION.

COMPOSITE HEAD FOR TACKS OR THE LIKE

Application filed August 30, 1922. Serial No. 585,280.

To all whom it may concern:

Be it known that I, HENRY B. TILTON, a citizen of the United States, residing at Portsmouth, county of Rockingham, State 5 of New Hampshire, have invented certain new and useful Improvements in Composite Heads for Tacks or the like, of which the following is a specification.

This invention relates to tack heads and 10 similar articles and particularly to a headed tack of general usefulness but particularly well adapted for electrical work as in the running of wires and the like. In any such use where a tack head is subjected to rather 15 violent treatment in driving in all kinds of woods and where it has to be depended upon to retain one or more strands of wire or other material, and especially where it is subject to considerable variations in moisture 20 and temperature the problem of providing anything in the character of a reasonably insulated headed fastening is difficult. Without going into further detail of the exacting requirements or the difficulties of meeting 25 them, all of which are well known in the trade, I will pass immediately to the discussion of an illustrative embodiment of my invention which I shall show and describe as a composite headed tack of a style employed 30 on telephone work and other electrical work, as such an embodiment well illustrates the principles involved and is of itself of immediate commercial value and utility.

Throughout the specification and drawings like reference characters are employed 35 to indicate corresponding parts, and in the drawings:

Fig. 1 is an enlarged sectional view of a tack in accordance with my invention.

Fig. 2 a bottom view of such a tack.

Figs. 3 and 4 a top and edge view of a tack core.

Fig. 5 a core and tack assembled.

Fig. 6 a similar view with the head formed.

Fig. 7 a plan view of a cover disc.

Fig. 8 a sectional view of the partly formed cover.

Fig. 9 a sectional view indicating the completion of the covering.

Referring to the embodiment shown in the drawings it will be seen that this tack comprises a shank 1 which may be of any usual style or length or gage of wire and a composite head member. This head may have

any desired shape or external finish, but it 55 comprises a core 2 preferably of a soft fibrous material and an outer shell or casing 3 preferably of a more tough and somewhat ductile fibrous material such as one of the fibre or leather boards. 60

I have endeavored to illustrate in Fig. 1 a section through the head of such a tack so as to illustrate its construction and characteristics. In forming such a tack in accordance with my invention I preferably cut a small 65 blank of the fibrous material such as button board in the form of a blank 2' as indicated in Figs. 3 and 4. This blank is very easily pierced by the shank of the tack 1 as indicated in Fig. 5 and the head blank or core is 70 then brought to approximate shape as indicated at 2², Fig. 6.

I also prepare a blank disc 3' which is 75 died out from flat stock, Fig. 7, and then partially form it into a shell 3², Fig. 8. The 80 blank 3' is considerably larger than the diameter of the blank 2' or the formed head core 2². When drawn or pressed to the formed shell 3² it is still somewhat larger than the head or head core 2², there being 85 sufficient stock left in the edges of the cup to be drawn down over the edge of the head core 2² and beneath the same.

The partly formed shell 3² may be conveniently 90 drawn about the head core 2² as indicated in Fig. 9. In this figure the shell 3² is retained within a female die A shaped to the ultimate form of the head, and the tack of Fig. 6 is supported in a male die B which is slightly concaved at its upper edge, as indicated at B', Fig. 9, to permit the edge of the shell 3² to be turned in under the head 2² and compressed when the dies are brought together.

The tack head is now substantially in 95 final form with the tougher outer shell 3 closely drawn over and compressed about the softer more absorbent head core 2. See Fig. 1. The tack heads are then impregnated to establish a more intimate union of 100 the parts and to render the composite head more resistant both as to strength to withstand blows and strains and also to withstand the various atmospheric conditions, particularly moisture. 105

In impregnating the head the soft fibrous head core 2 readily takes up suitable solutions or treatments. These may be of an

oily or gummy character or both, as for example, drying oils or oils and gums. Such treatment strikes through the fibrous head core 2 not only impregnating it but reaching 5 through to the interior of the shell 3 which is thus brought into firm union with the core 2 while the entire interior is hardened as to its structure and waterproofed. The coating further strikes in from the exterior so 10 that a comparatively complete degree of impregnation of the composite head takes place after the tack is made and the head mechanically formed. The heads may be dried or baked as desired to hasten or facilitate 15 the setting of the treatment.

Tacks formed with such heads so treated have an unusual degree of strength and a very high resistance to moisture. They are substantially nonconductors and may be 20 driven in even the harder woods without rupture of the head or shell and may also be successfully withdrawn without strip-

ping the head and leaving the sharp tack as a menace to the hands or clothing.

Various modifications may be made in the 25 parts and method of assembly and in the manner of treatment all without departing from the spirit of my invention if within the limits of the appended claim.

What I therefore claim and desire to secure by Letters Patent is:—

An article of the class described, comprising an absorbent core, a fastening member projected through said core, a shell of moldable fibrous material formed about said core 35 and projecting under the lower face of the same, said core and shell being impregnated with a liquid penetrant dried therein.

In testimony whereof I affix my signature in presence of two witnesses.

HENRY B. TILTON.
